UNITED STATES PATENT OFFICE.

NATHANIEL FISH AND HENRY HODGKINSON, OF DARWEN, ENGLAND.

MECHANISM FOR PUTTING COVER ON CLOTH IN LOOMS FOR WEAVING.

1,022,229.

Specification of Letters Patent.

Patented Apr. 2, 1912.

Application filed October 21, 1909. Serial No. 523,915.

To all whom it may concern:

Be it known that we, NATHANIEL FISH and HENRY HODGKINSON, residing at Darwen, in the county of Lancaster, England, 5 have invented new and useful Improvements in Mechanism for Putting Cover on Cloth in Looms for Weaving, of which the following is a specification.

An objectionable feature in weaving is 10 that the cloth often presents a raw, uneven, or reedy appearance caused by the cloth being badly or insufficiently covered. Faults in the cloth such as thick and thin places are also more in evidence, and the cloth 15 on the whole in consequence is inferior in quality.

Our invention is designed to improve the general appearance of cloth woven in looms by putting cover on the cloth by mechanical 20 means, the action of which consists essentially in imparting a vibratory movement, from the oscillation of the slay, to the back rod, or a rod used in substitution for the back rod of the loom, or any other con- 25 trivance to raise the top warp threads, so as to tighten them at the moment of the "beat up" thereby putting cover on the cloth, the attachment being made between the back rod or the like and the hand-rail! 30 of the loom for obtaining the required effect.

For attainment of the object of our invention, an attachment is made between the hand-rail and an arm mounted on a shaft 35 and communicating motion to two arms or collars also mounted on the same shaft, whereby with the forward movement of the slay, the last named arms will be raised, or the collars rotated partially, and will 40 raise the back rod or the like, or its equivalent to produce the like effect through the medium of an attachment between them and such back rod or the like.

Our invention will be fully understood 45 by reference to the annexed drawings, wherein—

Figure 1 is a back view of a loom top, while Fig. 2 is a sectional elevation of a loom fitted with our invention.

50 In these views, a piece of leather or other flexible or suitable material 1 is fixed to the slay-cap or hand-rail 2, and by means of a cord 3 a link 4 and a cord 5 is connected to an arm 6 mounted on rock shaft 7. This shaft

is carried by L brackets 8 bolted to the loom 55 top behind the loom. A collar or the like 9 may be fixed to the shaft to prevent end movement. Fixed near each end of the shaft is an arm 10, or a collar or the like fixed at each end may be substituted for the 60 arms. Between these arms or collars and the back rod 11 a suitable connection is made. This connection consists of a leather strap 12 fitted to leather loops 13 retained in position by the cord 14 which passes 65 through them, and holds the back rod, or its equivalent. End movement of the back-rod is thereby prevented. With the oscil- 70 lation of the slay, the top warp threads are tightened at the moment of the beat-up, thus putting cover on the cloth.

In a loom having a warp-stop motion, in which the back rod is dispensed with, we place, as an alternative, just behind the pin- 75 box of the warp-stop motion, a rod which is put beneath, instead of between, the sheet of warp threads coming from the warp-beam, and which is connected by attach- 80 ments to the arms 10 in a similar manner to the arrangement already described.

In a modification, the shaft 7 may be a fixture, and motion communicated to bell- 85 crank levers loosely mounted on the shaft by attachments between them and the slay- cap or hand-rail, the opposite ends of the bell-crank levers being connected to the back-rod by suitable attachments.

It will be perceived from the foregoing description and from a perusal of the annexed drawings, that instead of the said 90 means intermediate of the back rod or the like and the hand rail or other part of the slay, other means may be adopted for pro- 95 ducing the desired effect from the oscilla- tion of the slay, and all such means, we should consider as falling within the scope 95 of this invention.

What we do claim as our invention and desire to secure by Letters Patent is:—

A device for putting cover on cloth which 100 comprises, in combination with the hand rail and the back lease rod of the loom, a horizontal rock shaft supported at the top of the loom and provided with oppositely 105 projecting arms, link connections between the hand rail and an arm at one side of the rock shaft whereby the shaft is positively rocked at the moment of beat up and

link connections between the back lease rod and the arms at the opposite side of the rock shaft whereby the back lease rod is perpendicularly lifted when the shaft is 5 rocked in the manner and at the time aforesaid.

In testimony whereof, we have signed our

names to this specification in the presence of two subscribing witnesses.

NATHANIEL FISH.
HENRY HODGKINSON.
